GAGING MEANS FOR TOPLIFT ATTACHING

Harold Lane, Leicester, England, assignor to United Shoe Machinery Corporation, Flemington, N.J., a corporation of New Jersey

Application March 20, 1958, Serial No. 722,698

Claims priority, application Great Britain April 23, 1957

11 Claims. (Cl. 1—137)

This invention relates to fastening inserting machines and, more particularly, is concerned with positioning or gaging means for locating a work piece into which fastenings are to be driven so as to insure that the fastenings will be driven in definite positions and in a definite arrangement or pattern in the work piece.

The attachment of toplifts to the heels of women's shoes is commonly effected by a series of fastenings which are driven flush with the tread surface of the toplift at a uniform distance from the periphery thereof. This operation may be performed by a machine of the type disclosed in United States Letters Patent No. 1,716,591, granted June 11, 1929, upon application of F. L. Mackenzie, having an edge gage for positioning a heel and toplift to be secured thereto so as to provide a constant and desired spacing of the fastenings from the periphery of the heel as the shoe is swung from one side to the other to cause the fastenings to be arranged in a row about the margin of the toplift.

It is desired not only that the fastenings be spaced uniformly from each other, but also that the endmost fastenings of the row be uniformly spaced from the heel breast. Whether the work is fed by hand only or with the aid of feeding means associated with the machine, which facilitates uniform spacing of the fastenings from each other, uniform spacing of the endmost fastenings of the row from the heel breast cannot be obtained without the use of judgment and considerable skill on the part of the operator. Accordingly, the pattern of the fastenings is likely to be inaccurate and variable from shoe to shoe. In very small heels which permit the use of only a very few fastenings, such as three for example, inaccuracy in the placement of the fastenings may affect considerably the appearance of the heel as well as the sureness with which the toplift is attached to the heel.

In view of the foregoing, it is a principal object of the invention to facilitate the driving of fastenings, for securing a toplift to a heel, in predetermined positions and in a predetermined pattern without requiring skill or judgment on the part of the operator.

To this end, there is provided by the invention, in accordance with one feature thereof, a gage for positioning a work piece with respect to the fastening inserting mechanism of a machine of this type, the gage being mounted for movement in mutually transverse directions, and being positioned in any of a number of predetermined positions, in response to the presentation of the work piece to the machine, by stops with which the gage is selectively brought into engagement. Thus, by presenting the work piece, always in the same orientation with respect to the machine, to the fastening inserting mechanism in the predetermined positions determined by the engagement of the gage with the appropriate stops, accurate placement of the fastenings in each work piece and a uniform pattern of the fastenings from one piece to another are obtained.

Provision is also made in the illustrated machine, in

2

accordance with a further feature of the invention, for oppositely biasing the gage laterally thereof into a central position opposite to one of the stops which is arranged to co-operate with the gage, in response to rearward movement of the gage into engagement with the stop to position the gage laterally and rearwardly thereof simultaneously. Thus, the positioning of the work piece for the reception of the central fastening of the fastening pattern is readily effected.

10 Other stop means at each side of the above-mentioned stop is selectively engageable by the gage upon its being moved laterally and rearwardly thereof for determining the positions of other fastenings at each side of the central fastening.

15 The above and other features of the invention, including provisions for the adjustment or interchangeability of the stops to secure any desired arrangement and pattern of fastenings, will now be described in detail in the following specification and will be set forth in the appended claims.

In the drawings,

Fig. 1 is a side elevation illustrating an application of gage structure embodying the invention in a fastening inserting machine;

25 Fig. 2 is a sectional plan view of the gage structure of Fig. 1, the section being taken along the line II—II;

Fig. 3 is a front elevation of the structure shown in Fig. 2; and

30 Fig. 4 is a plan view of an alternative gage construction.

The illustrated gage structure is disclosed herein as associated with a fastening inserting machine of the type disclosed in the above-mentioned Mackenzie patent, and has means for forming fastenings from a coil of wire 35 and for driving the fastenings through a nozzle 10 (corresponding to the nozzle 26 of Mackenzie) into a toplift T and a heel H to which the toplift is to be attached. The heel H is supported by a wedge block 12 which rests upon a support 14 (corresponding to the support 72 of Mackenzie), the inclination of the block 12 being such as to cause the tread surface of the heel to be horizontal.

35 The toplift T and the heel H are positioned relatively to each other upon being brought into engagement with a gage 16 comprising a plate 18 having a V-shaped notch 20, adapted to receive the heel, to which plate there is 40 fixed a second plate 22 having a similar V-shaped notch 24 adapted to receive the toplift.

45 The plate 22 is fixed upon the plate 18 with the notch 24 offset rearwardly from the notch 20 whereby the toplift, which normally is slightly larger than the surface of the heel to which it is to be attached, will overlap the periphery of the heel.

50 The plate 18 is mounted for movement laterally and rearwardly thereof between a cover 26 and a support 28 which are secured to the head 30 of the machine by bolts 32 so that the upper surface of the plate 22 is just below the nozzle 10. The cover and support are separated from each other by spacing members 34, 36 to permit the above-mentioned movement of the plate 18.

55 60 In the plate 18 there is formed a rectangular recess 38 which receives an arm 40 of a cross slide 42 with respect to which the plate 18 slides freely lengthwise thereof and forwardly and rearwardly of the nozzle 10. The cross slide 42 has a second arm 43 which is perpendicular to the arm 40 and is received freely to slide in a recess 44 formed in the cover 26 transversely thereof. The gage 16 is thus mounted for movement, parallel to itself, forwardly and rearwardly thereof as well as laterally thereof.

65 70 Opposite to the ends of the arm 43, a pair of screws 46, 48 are threaded in the sides of the cover 26 and serve as stops for limiting movement of the slide 42, and hence

the gage 16, laterally thereof. A pair of light springs 50, 50 are compressed between the ends of the arm 43 and shoulders at the ends of the recess 44 whereby the slide 42 and gage 16 are biased laterally thereof into a central position with respect to the nozzle 10. The gage is also biased forwardly thereof, into its normal inoperative position, by a spring 54 which is compressed between the forward end of the arm 40 and a shoulder on the plate 18 at the forward end of the recess 38, whereby the plate 18 at the rear end of its recess 38 is normally held yieldingly in engagement with the rear end of the arm 40.

When a work piece is presented to the machine for the insertion of three fastenings, as in the case of the work piece illustrated herein, the heel H and the toplift T are seated within the notches 20, 24, respectively, and are moved rearwardly against the resistance of the spring 54 until a finger 56, projecting rearwardly from the plate 18, engages a conically pointed stop screw 58 which is threaded into a lug 60, the latter being fixed upon the rear ends of the cover 26 and support 28. The finger 56 is grooved to receive the end of the screw 58 so that, in response to rearward movement of the gage into complete engagement within the screw, the gage is positioned laterally thereof at the same time that it is positioned rearwardly thereof. Thus, the work piece is positioned for the insertion of a fastening at the center of the rear portion of the toplift.

After this fastening has been driven and upon relieving the pressure of the work piece against the gage to permit it to move forwardly out of engagement with the screw 58, the work piece is moved laterally to cause one end of the arm 43 to be brought into engagement with that one of the screws 46, 48 which is adjacent thereto. Simultaneously with this lateral movement of the gage, the work piece is also moved rearwardly to cause a stop screw 62, which is threaded into the plate 18 to be brought into engagement with the forward end of the arm 40. The work piece is thus positioned properly, both laterally and rearwardly of the nozzle 10, to receive one of the forward fastenings at one side of the heel. Similarly, after driving this fastening, the rearward pressure of the work piece against the gage 16 is relieved to permit the finger 56 to clear the screw 58 and the gage is moved laterally and rearwardly of the machine to the other side to position the work piece properly for the reception of the third fastening.

It is evident that, according to the adjustment of the adjusting screws 46, 48, 58 and 62, the work piece may be positioned to cause each fastening to be located in any desired position without requiring skill or judgment on the part of the operator and, obviously, the pattern of the fastenings from heel to heel will be invariable.

In an alternative gage structure shown in Fig. 4, a gage 64, corresponding to the gage 16 above described, is pivotally mounted upon a stud 66 for movement laterally of the nozzle 10. The stud is carried by a block 68 which slides forwardly and rearwardly in a recess 70 formed in a cover 72 corresponding to the above-mentioned cover 26. The gage 64 may be oppositely biased laterally thereof by springs 73, 73, similar to the springs 50, 50, into a central position. Likewise, the block 68 may be biased forwardly thereof by a spring 73a similar to the above-described spring 54, yieldingly to hold the gage in its normal inoperative position.

Upon presenting a work piece to the gage 64 and moving the work piece directly rearwardly, a rearwardly pointed end 74 of the gage is seated within a V-shaped notch 76 formed in an abutment 78 which is effectually integral with the support 28. The work piece is thus properly positioned to receive a fastening in the rear central portion of the heel. Upon relieving the rearward pressure of the work piece against the gage 64, the work piece may then be moved laterally and rearwardly to cause the end 74 of the gage to become seated in

each of two recesses 80, 82 in the abutment at either side of and behind the notch 76 whereby the work piece is properly positioned to receive a fastening at each side thereof adjacent to the heel breast.

There may be provided for use with this alternative gage construction a number of abutments, similar to the abutment 78 and interchangeable therewith, having notches, like the notches 76, 80, 82, but different in number, spacing or arrangement in accordance with the different sizes or kinds of work pieces to be operated upon.

In the use of the first-described gage structure, a heel H with a toplift T placed thereon are presented to the gage 16 with the toplift T seated against the plate 22 within the notch 24 and with the heel similarly seated against the plate 18 within the notch 20. The heel is presented to the machine with its longitudinal center line, corresponding to the longitudinal center line of a shoe to which the heel is to be attached, substantially in alignment with the fore-and-aft center line of the gage 16 through the vertices of the notches 20, 24. With the heel held in this orientation with respect to the machine throughout the toplift attaching operation, it is first moved directly rearwardly to move the gage 16 from its normal inoperative position into engagement with the screw 58 which will have been adjusted to effect the desired spacing of the rearmost fastening from the periphery of the heel. The position of this fastening laterally of the heel is determined by the engagement of the finger 56 and screw 58, which co-operate to cause the gage to be moved slightly one way or the other into alignment with the screw 58.

After the rearmost fastening has been driven, the operator allows the gage to move forwardly out of contact with the screw 58 and then, keeping the orientation of the heel the same as before, moves it to one side or the other. If, for example, the heel is moved to the left the cross slide 42 is brought into engagement with the screw 46. Simultaneously with this lateral movement of the gage, it is also moved rearwardly to bring the screw 62 into engagement with the cross slide whereby the work is completely positioned for the insertion of a fastening in the right forward margin of the heel (as viewed toward the tread surface thereof).

Again, without changing the orientation of the heel it is moved forwardly enough to permit the finger 56 to pass the screw 58 and then is moved to the right and rearwardly, simultaneously, to bring the cross slide 42 into engagement with the screw 48 and the screw 62 into engagement with the cross slide. The work piece is thus positioned properly for the reception of a fastening at the left forward margin of the heel. Uniform spacing of the forward fastenings from the heel breast is insured by the fact that the rearward movement of the gage 16 is limited in both instances by the stop screw 62.

Similarly, in the use of the alternative construction, the work piece is presented to the gage 64 and, with no change in the orientation of the work piece to the machine, it is moved to cause the pointed end 74 of the gage to be brought selectively into the notches 76, 80 and 82 whereby the work is properly located for the reception of each of the three fastenings, as illustrated.

Having thus described my invention, what I claim as new and desire to secure by Letters Patent of the United States is:

1. In a machine of the class described having fastening inserting mechanism, a gage for positioning a work piece presented to said machine in any of a number of spaced operative positions, said gage being mounted for movement laterally and rearwardly of said mechanism in response to the pressure of a work piece held thereagainst, and plural stop means cooperating with said gage selectively to position it in one operative position with respect to said mechanism and in another operative position at one side of said one operative position.

2. In a machine of the class described having fastening inserting mechanism, a gage for positioning a work piece presented to said machine in any of a number of operative positions spaced from each other laterally and rearwardly of said mechanism, said gage being mounted for yielding movement laterally and rearwardly of said mechanism in response to the pressure of a work piece held thereagainst, and plural stop means cooperating with said gage selectively to position it in one operative position centered laterally with respect to said mechanism and in each of two other operative positions at each side of said one position and disposed rearwardly thereof.

3. In a machine of the class described having fastening inserting mechanism, means for positioning a work piece with respect to said mechanism comprising a gage mounted for movement laterally and rearwardly of said mechanism into different operative positions, and stop means for selectively positioning said gage in one operative position disposed centrally of said mechanism and in an operative position at each side and rearwardly of said one operative position.

4. In a machine of the class described having fastening inserting mechanism, a gage mounted for movement laterally and rearwardly of said mechanism in response to the presentation of a work piece to said machine, stop means for centering said gage laterally of said mechanism and simultaneously limiting rearward movement of said gage whereby said gage is located in one operative position, and other stop means for limiting lateral movement of said gage toward each side of and rearwardly of said mechanism whereby the work piece is located in other operative positions having a predetermined relation to its first-mentioned operative position.

5. In a machine of the class described having fastening inserting mechanism, means for positioning a work piece with respect to said mechanism comprising a gage, a support having a plurality of stops, said gage being mounted for yielding movement upon said support in mutually transverse directions into engagement with said stops selectively whereby said gage is positioned selectively in different operative positions.

6. In a machine of the class described having fastening inserting mechanism, means for positioning a work piece with respect to said mechanism comprising a gage mounted for movement laterally of said mechanism and forwardly and rearwardly thereof, means for biasing said gage forwardly of said mechanism, means for biasing said gage from each side of said mechanism toward the other, and plural stop means arranged to cooperate selectively with said gage in response to the presentation of a work piece to the machine for positioning the work piece in an operative position determined upon the engagement of said gage with the selected stop means.

7. In a machine of the class described having fastening inserting mechanism, means for positioning a work piece with respect to said mechanism comprising a gage

5 mounted for movement laterally and rearwardly with respect to said mechanism, means for biasing said gage forwardly of said mechanism and laterally thereof in opposite directions, a stop for positioning said gage laterally and rearwardly of said mechanism in response to presentation of the work piece to the machine whereby said gage is located in one operative position, and stop means for limiting rearward and lateral movement of said gage at each side of said one position.

8. In a machine of the class described having fastening inserting mechanism, a gage for positioning a work piece with respect to said mechanism, a member upon which said gage is mounted to slide rearwardly of said mechanism, a support upon which said member is mounted to slide laterally of said mechanism, stop means upon said support arranged to co-operate with said member to limit lateral movement of said gage toward each side of said mechanism, stop means carried by said support for limiting rearward movement of said gage and positioning it laterally of said mechanism whereby one operative position of said gage is determined, and stop means between said gage and member arranged to co-operate with said first mentioned stop means to position said gage in other operative positions at each side of said one position.

9. In a machine of the class described having fastening inserting mechanism, a support having a plurality of stops, and a gage mounted to swing laterally thereof and to slide rearwardly thereof into engagement with said stops selectively whereby said gage is positioned in response to the presentation of a work piece thereto.

10. In a machine of the class described having fastening inserting mechanism, a support having a plurality of stops, a slide mounted upon said support for movement forwardly and rearwardly of said mechanism, and a gage pivotally mounted upon said slide for movement laterally of said mechanism, said gage being movable in response to the presentation of a work piece thereto into selective engagement with said stops.

11. In a machine of the class described having fastening inserting mechanism, means for positioning a work piece with respect to said mechanism comprising a stop member having a plurality of notches, and a gage mounted to swing laterally of said mechanism and to slide rearwardly of said mechanism, said gage being movable into selective engagement with said notches in response to the presentation of the work piece to said gage whereby the work piece is located in a position corresponding to each of said notches.
